[57] CLAIM

The ornamental design for a combined closure flap and lock for luggage or the like, as shown and described.

DESCRIPTION

FIG. 1 is a combined closure flap and lock for luggage or the like showing the parts in normal operative position; it being understood that the bottom of the lock member is plain and unornamented;

FIG. 2 is a perspective view thereof with the flap disengaged and folded back exposing the stud; and

FIG. 3 is an enlarged scale top plan view thereof in an operative position.

Fig. 3.
